Primary Examiner — Elizabeth J Oswecki(74) *Attorney, Agent, or Firm* — Gary L. Bush; Andrews Kurth LLP(57) **CLAIM**

The ornamental design for a sauté spoon, as shown and described.

DESCRIPTION

FIG. 1 is a front view of a sauté spoon showing our new design;

FIG. 2 is a front, left, bottom perspective view thereof;

FIG. 3 is a rear, right, bottom perspective view thereof;

FIG. 4 is a front, left, top perspective view thereof;

FIG. 5 is a rear, right, top perspective view thereof;

FIG. 6 is a bottom plan view thereof;

FIG. 7 is a top plan view thereof;

FIG. 8 is a cross sectional view taken along lines 8-8 of FIG. 1;

FIG. 9 is a cross sectional view taken along lines 9-9 of FIG. 1;

FIG. 10 is a right side view of FIG. 1;

FIG. 11 is a rear view thereof; and,

FIG. 12 is a left side view thereof.

The broken lines in FIGS. 1, 2, 3, 4, 5, 6, 10, 11, 12 form no part of the claimed design.

1 Claim, 4 Drawing Sheets---
